UNITED STATES PATENT OFFICE

1,925,994

APPARATUS FOR INTERRUPTING ALTERNATING POWER CIRCUITS

Frank T. Chesnut, Trenton, N. J., assignor to
 Ajax Electrothermic Corporation, Ajax Park,
 N. J., a corporation of New Jersey

Application February 23, 1929. Serial No. 342,282

6 Claims. (Cl. 175—294)

My invention relates to disconnection of alternating current power circuits.

The main purpose of my invention is to provide for opening a plurality of alternating current power circuits one at a time through the same disconnecting mechanism.

A further purpose is to provide for throwing a resonated reactance in parallel with the current supplies for alternating current power circuits, one circuit at a time, then opening the supply to the particular circuit with which the resonated reactance is in parallel and subsequently opening the circuit through the resonated reactance and repeating the operation with the same resonated reactance for the other circuits as they require disconnection.

Further purposes will appear in the specification and in the claims.

I have illustrated my invention purely diagrammatically and by one form only, selecting a form which is practical, efficient and thoroughly reliable and which at the same time well illustrates the principles of my invention.

Figure 1 shows diagrammatically a plurality of power circuits with disconnecting means adapted to be effective, one at a time, with any of them.

Figure 2 shows operation of diagrammatic circuits from a distant point.

The generator 9 is intended to be typical of the different types of alternating current sources of supply available and is not intended to be restricted to the normal rotary generator of commerce.

This generator is shown in Figure 1 as supplying alternating current to a number of power circuits having different characteristics, to indicate that the application of my invention is independent of the character of circuit interrupted.

In one of these circuits a resistance load 10 is shown. In a second an inductive load 11 appears, with resistance 10' separately shown but intended to include the resistance inherent to the inductive load as well as any outside resistance which may exist in the circuit. In the third connection a resonant circuit is supplied, comprising an inductance 11' and capacity 12. All of these circuits are connected across current supply lines 13 and 14 through suitable switches. A wave trap is used which is capable of operation with any of the circuits. I have illustrated one such trap comprising a resonated circuit having capacity 15 and inductance 16.

The wave trap is adapted to be connected between one of the lines, such as line 14, and the

load, in parallel with the normal connection of this load with the line so that the same wave trap may be used to parallel the normal connections between any of the loads and the line.

The character of switch or switches by which the wave trap and the normal connection of the load with any line are placed in parallel, one at a time, for any of the loads, and by which the connections are subsequently opened, is not important, provided that it is capable of performing the required function; and the character of switch will, therefore, be determined upon the basis of the simplicity, reliability and convenience of the switch as distinguished from any supposed novelty in the switch itself. Two such types of switches are shown. One is intended to represent a spring contactor but for convenience of illustration is shown as provided with knives movable laterally across the contacts.

The loads are shown in Figure 1 as connected with the line normally through switch arms 17, contacts 18 and conductors 19. Each switch arm 17 is electrically connected with a switch arm 20 which is adapted to engage or break contact with a contact 21 without opening the engagement of switch arm 17 with its contact 18. A third contact 22 provides convenient resting place for arm 17 when its engagement with contact 18 is broken.

The wave trap is connected between line 14 and the several contacts 21, one for each circuit to be opened.

In operation the current for the loads normally passes through switches 17, 17' and 17² and their connections 19. To interrupt the circuit supplying any of the loads, such as that through switch 17', the wave trap is connected in parallel with the corresponding connection 19, as by closing switch 20' against contact 21. The current through connection 19 can then be interrupted by opening switch 17' as shown in the dotted position of this switch. This is permissible because the condenser of the wave trap will take up the surge which would otherwise cause arcing, and this surging current will be distributed in the wave trap instead of causing trouble at the switch. The current through the wave trap can then be interrupted by opening the switch 20' without any arc. This interruption of the circuit connection to or from the wave trap can take place at switch 20'.

Where the switch 20' is opened it can be turned to some such position as the dotted position of 20².

When it is desired to connect a load again in

its normal circuit the corresponding switch 17, 17' or 17² is closed.

It is convenient but by no means necessary to couple the switches 17 and 20, 17' and 20', 17² and 20² respectively so as to permit independent movement between them throughout a limited range of separation and to require that the two switches shall move together when the limit of separation has been exceeded. The separation 10 should be sufficient to permit the two switches to engage contacts 18 and 21, 18' and 21', etc. at the same time, carrying switch 17 with switch 20, for example, in counter-clockwise movement in Figure 1 after the limit of movement has been 15 reached, and closing switch 20 against switch 17, for example, with clockwise movement in the figure so that but one switch need be operated in each direction. During this last (restoring) movement of the switch arms, switch 20 will 20 momentarily close the circuit through the wave trap unless the circuit meantime be interrupted at some other point.

In the diagram switches 17, 17' and 17² are shorter than switches 20, 20', 20², so as to avoid 25 engagement of these switches with the contacts 21, 21', 21².

In Figure 2 I have applied the invention to 30 parallel operation of a number of specific devices in the same art, here a plurality of tuned furnace inductor circuits having inductors 11 and condensers 12 each, each furnace supply circuit of which can be interrupted by the wave trap mechanism common to all.

In order to indicate that the character of switch 35 is not controlling I have illustrated different switch mechanism in Figure 2 from that in Figure 1. Figure 2 shows pairs of contactor blades 23 and 24, one pair for each load circuit. The contactor fingers are spaced by insulating material 40 25 and, until the electromagnets are energized, are spring retracted by any suitable spring 26.

The contactor blades are electromagnetically 45 operated in any suitable way as by electromagnets 27 whose coils receive current from a line 28 through appropriate individual switches 29.

The blades engage contacts 30 and 31 which 50 are so spaced and proportioned that in the position of the blades dotted at 23', 24' both blades are closed against their contacts while in the position 23², 24² the blade 24 is closed against its contact and the blade 23 is open.

When electromagnetically controlled, the load 55 circuit is connected to the line uninterruptedly through the contact 31, blade 24 and connection 32, but when it is desired to open any circuit, de-energization of the electromagnet 27 permits the spring 26 to shift both blades to the left to the position shown in solid lines.

Starting with the switch position shown in solid 60 lines at the left in Figure 1 when the proper electromagnet is energized the switch will move in clockwise direction and will, in passing, momentarily include the wave trap in the circuit during its movement to the final position in which the load is connected to the line. This momentary connection takes place while knife 23 is passing over contact 30 and is not objectionable. When knife 24 engages contact 31 a part of the load 65 circuit is placed in parallel with the wave trap circuit, and this condition continues until knife 23 leaves contact 30 and breaks this wave trap connection. The load circuit path through switch knife 24 and connection 32 is then the only load 70 circuit path to the line at this point. This is the switch position for furnace operation.

When the coil of the electromagnet is deenergized, either through failure of current or by 80 opening the appropriate switch, the blades 23 and 24 are retracted by the spring, moving in counter-clockwise direction. By this movement a wave trap similar to that in Figure 1 is first introduced in parallel with a portion of the load circuit which passes through the switch and connection 32, and the circuit through connection 32 is then opened while the wave trap is still connected to receive and to distribute within the trap the surge of current due to the opening of the main circuit. The circuit through the wave trap is then opened and the switch comes to rest in the position shown in Figure 2.

As will be seen the automatic control of the succession of contacts made in opening and closing the blades 23 and 24 ensures the proper order of these contacts and fully protects against accidental or erroneous connection of the circuits. Electromagnetic control of the several devices 95 permits thorough and reliable control of the circuits at a distance so as not only to open and close the circuits but to ensure inclusion of the wave trap in parallel with the portion of the circuit to 100 be interrupted up to the time of interruption of the main circuit.

It will be evident that I have provided mechanism common to any number of circuits to be interrupted which will open these circuits with- 105 out substantial arcing.

It will be evident that whether a split switch or independent switches, or a multipolar switch be used the function is the same of throwing the common wave trap into parallel with the circuit 110 to be interrupted, maintaining the connection through the wave trap while the current path to the load through the paralleled circuit is interrupted and subsequently interrupting the wave trap circuit.

In view of my invention and disclosure variations and modifications to meet individual whim or particular need will doubtless become evident to others skilled in the art, to obtain all or part of the benefits of my invention without copying 120 the structure shown, and I, therefore, claim all such in so far as they fall within the reasonable spirit and scope of my invention.

Having thus described my invention what I claim as new and desire to secure by Letters 125 Patent is:—

1. A plurality of alternating current power circuits in combination with a wave trap circuit containing means common for each of the circuits for interrupting each of the circuits and 13 means respectively for connecting the wave trap circuit in parallel with a part of any circuit, for subsequently opening the part of the circuit so paralleled and for finally opening the circuit through the wave trap.

2. A plurality of alternating current power circuits, in combination with a wave trap circuit for interrupting each of the power circuits and means respectively for connecting the wave trap circuit in parallel with a part of any circuit, and 140 for subsequently opening the part of the circuit so paralleled.

3. An alternating current power circuit, a switch in said circuit, a wave trap connected to parallel the part of the power circuit containing 145 said switch, a switch in the connection to the wave trap, circuit connections between the two switches whereby, beginning with the switch in the power circuit closed, the wave trap circuit is closed and the power circuit is subsequently 150

opened, and electromagnetic distant controlled means operating said switches in a direction to open the switch in the power circuit and to subsequently open the switch in the wave trap circuits.

4. A plurality of alternating current power circuits, a common source of current supply, a wave trap connected at one side with one side of the source of supply and switch means for inserting the wave trap in turn within the different alternating current power circuits.

5. In an electrical system, a plurality of alternating current power circuits, a circuit loop having two parallel branches, an inductance in one branch, a capacity in the other branch, means

for connecting the circuit loop in parallel with a portion of any one of the power circuits which is to be broken, means for breaking the paralleled portion of the power circuit to which the loop is connected and means for subsequently disconnecting said power circuit from said loop.

6. In an electrical system, a plurality of alternating current circuits, a switch in each circuit, a shunting circuit having a resonant loop, means for shunting any one of the switches by the shunting circuit and means for removing the shunt from said one switch after the switch has been opened.
